(57) **CLAIM**

I claim the ornamental design for a tool, as shown and described.

DESCRIPTION

FIG. 1 is a first perspective view of the tool;
 FIG. 2 is a top view of the tool;
 FIG. 3 shows a bottom view of the tool;
 FIG. 4 shows a first side view of the tool;
 FIG. 5 shows a second side view of the tool;
 FIG. 6 shows another side view of the tool;
 FIG. 7 shows another side view of the tool; and,
 FIG. 8 shows a cross sectional view of the tool.
